UNITED STATES PATENT OFFICE

156,671

PITCHER

Lawrence H. Russell, Saginaw, Mich.

Application July 28, 1947, Serial No. 140,561

Term of patent 3½ years

(Cl. D44—21)

To all whom it may concern:

Be it known that I, Lawrence H. Russell, a citizen of the United States, residing at Saginaw, in the county of Saginaw and State of Michigan, have invented a new, original, and ornamental Design for Pitchers, of which the following is a specification, reference being had to the accompanying drawing, forming part thereof.

Fig. 1 is a perspective side view of a pitcher, showing my new design;

Fig. 2 is a top plan view thereof;

Fig. 3 is a fragmentary view in vertical section showing the shape of the pitcher, Figs. 1 and 2, the section taken in the plane defined by the broken lines 3—3 in Fig. 2, and viewed in the direction of the arrows thereon.

I claim:

The ornamental design for a pitcher, as shown.
LAWRENCE H. RUSSELL.
